JAMES W. MOWBRAY, OF WINDSOR, ONTARIO, CANADA, ASSIGNOR, BY MESNE ASSIGNMENTS, TO GEORGE L. BROWN, OF PORT HURON, MICHIGAN.

CARBURETER.

1,209,747.

Specification of Letters Patent. Patented Dec. 26, 1916.

Application filed November 9, 1914, Serial No. 870,963. Renewed September 8, 1916. Serial No. 119,137.

To all whom it may concern:

Be it known that I, JAMES W. MOWBRAY, a subject of the King of Great Britain, residing at Windsor, Province of Ontario, Dominion of Canada, have invented a certain new and useful Improvement in Carbureters, and declare the following to be a full, clear, and exact description of the same, such as will enable others skilled in the art to which it pertains to make and use the same, reference being had to the accompanying drawings, which form a part of this specification.

This invention relates to carbureters and its object is a simple, inexpensive and efficient device for use in vaporization of hydro-carbon fuel for internal combustion engines.

A further object is a carbureter in which the fuel supply is directly proportional to the quantity of air passing therethrough, at all speeds of operation of the attached engine, in combination with a plurality of distinct atomizations of the fuel as it passes through the carbureter to the engine resulting in a standard carburation with more resultant power, less carbon deposits, and ease in starting.

An additional object resides in the means employed in relieving the fuel charge of excess pressure under high engine speed.

I am aware of other carbureters providing a fuel charge supplied from two sources, one of which is constant per unit of time, and one of which is variable per unit of time. This invention, therefore, relates more particularly to means, in combination with such compensating fuel supply, to more effectively break up or atomize the fuel and effect a higher degree of vaporization, whereby the mixture is more readily explosive and more completely burned in the cylinders.

These and other objects and various other novel features of construction by which they may be attained are hereinafter more fully described and claimed and shown in the accompanying drawing in which—

Figure 1 is a plan view of a carbureter embodying my invention. Fig. 2 is a vertical section of the Venturi tube taken on line $x-x$ of Fig. 1. Fig. 3 is a vertical section of the fuel chamber taken on line $y-y$ of Fig. 1. Fig. 4 is a vertical section taken substantially on line $z-z$ of Fig. 1. Fig. 5 is a plan view partly in section on a horizontal plane through the fuel conduit.

Similar characters refer to similar parts throughout the drawing and specification.

The carbureter consists of an air tube 1 having the shape of a Venturi tube provided with a throttle valve 2 of ordinary type and a shutter valve 3 near the intake end of the tube. The valve 2 is provided with a control lever 4 and the valve 3 is provided with a control lever 5 both of which may be operated from a remote point if desired. The stem 6 of the valve 3 is also provided with a coiled spring 7 tending to hold the valve full open at all times so that, upon release of the lever 5 after the valve has been partially closed, the valve is immediately returned to normal open position through operation of the spring 7.

Formed integrally with the air conduit 1 is a fuel chamber 8 having an inlet 9 at the bottom thereof, controlled by a needle valve 10, which is actuated through movement of a float 11 tending to maintain a constant fuel level in the fuel chamber in the manner well known with such devices. The chamber 8 is provided with an apertured cover 12 held in position by a screw threaded pivot 13.

Formed in an enlarged part of the fuel chamber wall are two wells 14 and 15 having passageways 16 and 17 respectively leading into the fuel chamber below the fuel level 10 therein as shown more particularly in Fig. 4. The fuel well 14 is provided with an air tube 18 extending downward thereinto preferably close to the bottom of the well and the upper end of the well is closed to atmosphere except through the interior of the tube. The tube is made smaller in diameter than the well thus allowing the fuel to rise about the exterior of the tube within the well.

The well 15 terminates at the upper end 95 in a seat 19 for a needle valve 20 by means of which the flow of fuel from the said well may be regulated. The body of the valve is threaded and provided with a head 21 by means of which it may be turned and a coiled spring 22 is also provided engaging against said head and the carbureter body with sufficient force to prevent accidental turning of the needle valve. Communicating with the upper end of both these wells is a passageway 23 leading to a channel 24 formed between two constituent parts of a secondary air conduit 25. The channel 24 is preferably V shaped being formed by the adjacent cone-shaped ends of the two parts 110

of the air conduit, the upper part of which is supported by the shoulder 26, and the lower part of which is supported in position by the shoulder 27. Both said parts 5 tightly fit in apertures in the wall of the air conduit 1 and are pressed into place. The lower end of the secondary conduit passes into the main air conduit 1 at the point of greatest restriction terminating near the 10 center thereof so that the fuel channel 24 is subject to the influence of air passing through the conduit 1. The two parts of the secondary air conduit are not quite in contact leaving a space of about one sixty- 15 fourth of an inch between the two sharp edges of said parts and thus air passing through the secondary air conduit draws the fuel from the channel 24 across and between these sharp edges which effectually breaks 20 up the globules of the fuel and aids in the atomization thereof.

An air passage 28 is provided in the passageway 23 between the two points at which the fuel from the wells enters the passageway. This air passage 28 leads into the fuel chamber above the fuel level therein whereby air is drawn into the said passageway 23 tending to primarily atomize the fuel from the said wells. In passing through the tube 30 23 and the conduit 24 into the secondary air passage 25, a second mixture of air with the fuel charge takes place so that the fuel is in quite finely divided state at the time it enters the main Venturi tube where the final atomization of the fuel is completed by reason of the air passing through the said tube 1 and across the lower end of the secondary conduit.

A passageway 30 is formed in the wall of 40 the Venturi tube leading into the interior of the tube at a point adjacent the edge of the throttle valve 2, when closed or nearly so, as is indicated in Fig. 5. The tube 31 provides a means of communication between 45 the fuel channel 24 surrounding the secondary air tube and the conduit 30. With the throttle nearly closed (at the time of starting the engine for instance) only a small volume of air passes through the main air 50 conduit 1 and, therefore an insufficient degree of vacuum is produced at the mouth of the secondary air conduit to draw fuel through said conduit but the rush of air past the edge of the throttle valve 2 is sufficient 55 to draw the fuel through the tube 31 and passageway 30 into the air tube 1. As the throttle is gradually opened the degree of vacuum at the mouth of the secondary air tube is increased and that at the mouth of 60 the passageway 30 is decreased until practically the entire fuel charge enters the main conduit through the secondary air conduit 25.

It is to be noted that the passageway 16 at 65 the lower end of the well 14 is small in size

restricting the flow to the said well while the aperture 17 in the bottom of the well 15 is practically of the diameter of the well so that the flow thereto is practically unrestricted and both said wells are subject to 70 atmospheric pressure. The constant fuel supply well 14, as before stated, is provided with an air tube 18 terminating near the bottom of the well and the function of this air tube is as follows:—When the engine to 75 which the carburetor is attached is idle, the fuel in the well 14 rises to the level of the fuel in the fuel chamber both inside and outside of the air tube 18. With the throttle tightly closed, if it be possible for the engine 80 to be operated under such condition, a high degree of vacuum would be produced on the engine side of the throttle, while no degree of vacuum on the carburetor side of the throttle would be produced. If the 85 throttle is partially open fuel is drawn into the main air conduit either through the secondary air conduit or the passageway 30, or both, and from both wells as heretofore described. As the suction on the oil wells 90 increases by further opening of the throttle, the level of fluid in the air tube 18 gradually descends while the fluid outside of the said tube passes into the fuel conduit 23. The tube 18 is made of such length that when 95 the throttle is about half open, the fluid will have passed entirely out of the air tube and air may be drawn through the tube into the said well reducing the suction therein, and air and gas will both pass up about the tube 10 into the fuel conduit thus partially relieving the fuel conduit of the influence of the vacuum and preventing too great an increase in the fuel supply under constant increase in vacuum. With an ordinary carburetor unprovided with such compensating device, the fuel supply, from the time the throttle valve is about one half open until it is fully open, is too great in proportion 10 to the volume of air, but, by partially relieving the oil from the influence of the vacuum produced in the tube after a certain degree of vacuum has been attained, the fuel supply is maintained in practically constant proportion to the air passing through the 11 conduit.

It is also to be noted that the sizes of the various conduits and apertures vary with the size of the carburetor and engines supplied thereby. In a one-inch carburetor supplying a four cylinder motor of about two and one-half inch or three inch bore and four inch stroke, I have found that the passageway 16 should be made with a No. 60 drill. The passageway 17 should be formed with a 12 No. 42 drill, and the two parts of the secondary air tube 25 should be set about one sixty-fourth of an inch apart. The primary air passage 28 should be formed with a No. 56 drill, and the passageway 25 through the 13

secondary air conduit should be made with No. 24 drill.

In starting of the engine, the throttle is very nearly closed which, as before stated, causes a rush of air past the mouth of the passageway 30, drawing fuel from both the wells 14 and 15, through the fuel channel 24 surrounding the secondary air tube. When the throttle is opened farther and the engine speeded up the greater volume of air drawn through the tube 1 causes a greater degree of vacuum at the mouth of the secondary air conduit and draws fuel from the channel 24 into the main air conduit substantially at the point of greatest restriction, and some fuel also will flow into the air conduit through the passage 30. When the throttle is fully opened the suction at the mouth of the tube 30 is reduced to a minimum, while that at the mouth of the secondary air tube is increased to a maximum, and little or no fuel enters the main conduit through the passage 30.

The flow of the fuel to the well 14 through the restricted passageway 16 is substantially constant. Consequently, as the engine speed is increased, the proportion of fuel from the said well to the volume of air passing through the carbureter decreases, thus providing a source of supply that is constantly poorer as the engine speed increases. The flow to the well 15 is variable per unit of time, that is, increases as the engine speed increases, in such manner that the supply from the said well is constantly increasing in richness in proportion to the air passing through the main conduit. By utilizing both sources of fuel supply, a fuel charge is provided that is constantly in proportion to the volume of air passing through the main conduit. This feature, however, is well known in the art. By introducing an air passage 28 in the fuel conduit 23 substantially as shown, the fuel is partially atomized as it passes into the conduit from the wells. By adding further air to the charge and breaking up the globules as they pass through the channel 24 into the secondary air-passage 25, a second atomization of the fuel takes place so that, at the time the fuel enters the main air conduit, it is in a finely divided state and, in passing into the main air conduit, is in condition to be thoroughly mixed with the air passing therethrough at which point the fuel is completely atomized. I, therefore, do not claim broadly the compensating fuel wells, but

What I do claim and desire to secure by Letters Patent of the United States is—

1. In a carbureter, an air conduit, a fuel conduit subject to the influence of air passing through the air conduit, a suction controlled fuel feed, a fuel feed giving a constant supply per unit of time, both said feeds being in communication with the fuel con-

duit, and a restricted air passage leading into the fuel conduit adjacent the points of communication of the fuel feeds therewith.

2. In a carbureter, an air conduit, a secondary air conduit leading thereinto, a fuel conduit discharging into said secondary conduit, a fuel feed variable per unit of time and a fuel feed constant per unit of time both discharging into the fuel conduit, and an air passage leading into the fuel conduit in proximity to the points of communication of the fuel feeds therewith.

3. In a carbureter, an air conduit having the form of a Venturi tube, a secondary air conduit leading thereinto substantially at the point of greatest restriction, a fuel conduit discharging into the secondary conduit, a fuel supply variable per unit of time and a fuel supply constant per unit of time both communicating with the fuel conduit, and a restricted air passage leading into the fuel conduit in proximity to the points of communication of the fuel supplies therewith.

4. In a carbureter, an air conduit having the form of a Venturi tube, a secondary air conduit leading thereinto substantially at the point of greatest restriction, said secondary conduit being of two parts spaced a slight distance apart and so formed as to provide a fuel channel about the said conduit communicating with the air conduit through the interstice between the said parts, a fuel conduit communicating with the said channel, a fuel supply variable per unit of time and a fuel supply constant per unit of time both communicating with the fuel conduit at separate points, and a restricted air passage leading into the fuel conduit between the points of communication of the fuel supplies therewith.

5. In a carbureter, an air conduit having the form of a Venturi tube, a secondary air conduit leading thereinto substantially at the point of greatest restriction therein, said secondary conduit being formed of two parts having cone-shaped ends providing sharp edges about the conduit opening and spaced a short distance apart forming a channel in communication with the secondary conduit, a fuel conduit communicating with said channel, a fuel supply variable per unit of time and a fuel supply constant per unit of time, both communicating with the fuel conduit, and a restricted air passage leading into the fuel conduit in proximity to the points of communication of the fuel supplies therewith.

6. In a carbureter, a throttle controlled air conduit having the form of a Venturi tube, a secondary air conduit discharging thereinto substantially at the point of greatest restriction, the secondary air conduit being formed of two portions set a slight distance apart and so formed on the adjacent ends as to provide a fuel channel communi-

cating with the air conduit through the interstice between the said parts, a fuel supply variable per unit of time, a fuel supply constant per unit of time both in communication with the channel, an air passage leading into the fuel conduit in proximity to the points of communication of the fuel supplies therewith, and a passageway leading from said fuel channel into the main air conduit 10 in proximity to the throttle valve when nearly closed.

7. In a carbureter, an air conduit having the form of a Venturi tube, a secondary air conduit leading thereinto at the point of 15 greatest restriction, a constant level fuel chamber, a fuel supply constant per unit of time having a restricted passageway at the bottom leading into the fuel chamber below the fuel level therein, a fuel supply variable 20 per unit of time also in communication with the fuel chamber below the fuel level, a fuel conduit subject to the influence of air passing into the secondary conduit, an air passage leading into the fuel conduit in proximity 25 to the points of communication of the fuel supplies therewith, said air passage leading into the fuel chamber above the fuel level therein, and a throttle valve for controlling the flow of air through the main 30 air conduit.

8. In a carbureter, a main air conduit having the form of a Venturi tube, a secondary air conduit leading into the main conduit at the point of greatest restriction, 35 the secondary conduit being formed of two parts having separated adjacent ends, a fuel channel formed about the secondary conduit and communicating therewith through the interstice between said ends, a fuel conduit 40 leading into said channel, a fuel supply constant per unit of time, and a fuel supply variable per unit of time both discharging into the fuel conduit, a constant level fuel chamber, a fuel passage for each of the fuel 45 supplies communicating with the fuel chamber below the normal fuel level therein, an air passage communicating with the fuel conduit in proximity to the points of communication of the fuel supplies therewith, 50 said passage leading into the fuel chamber above the normal fuel level therein, and a throttle valve controlling the main air conduit.

9. In a carbureter, an air conduit, a fuel 55 conduit subject to the influence of air passing through the air conduit, a fuel well having a restricted fuel inlet at the bottom adapted to provide a constant supply per unit of time, a fuel well having an inlet at

the bottom adapted to provide a supply 60 variable per unit of time, both said wells opening into the fuel conduit, and an air tube extending into the well of constant supply and terminating near the inlet providing the sole means for supplying air to said 65 well.

10. In a carbureter, a main air conduit, a secondary air conduit leading thereinto, a fuel conduit discharging into the secondary air conduit, a constant level fuel chamber, a fuel well adapted to provide a supply constant per unit of time, a second fuel well adapted to provide a supply variable per unit of time, both said wells discharging 70 into the fuel conduit and being in communication with the fuel chamber at the bottom, an air tube extending into the constant supply well and terminating below the normal fuel level therein providing the sole means of admitting air into the well, an air passage leading into the fuel conduit in proximity to the points of communication of the fuel wells therewith, said passage leading into the fuel chamber above the normal fuel level therein, and a throttle valve controlling 75 the flow of air through the main air conduit.

11. In a carbureter, a main air conduit having the form of a Venturi tube, a secondary air conduit leading thereinto at the 90 points of greatest restriction, said secondary air conduit being formed of two spaced parts formed to provide a circumferential fuel channel discharging into the conduit through the interstices between the parts, a fuel conduit discharging into the said channel, a constant level fuel chamber, a fuel well adapted to provide a supply constant per unit of time, a second fuel well adapted to provide a supply variable per unit of 95 time, both said wells discharging into the fuel conduit and being in communication with the fuel chamber at the bottom, the air tube extending into the constant supply well and terminating below the normal fuel level 100 therein providing the sole source of air supply for said well when the fuel in the tube has been drawn out by reason of the vacuum produced in the main air conduit and thereby relieving the fuel conduit of excess pressure due to said vacuum.

In testimony whereof, I sign this specification in the presence of two witnesses.

JAMES W. MOWBRAY.
